United States Patent Office

Des. 210,489

Patented Mar. 12, 1968

210,489

CASH CONTROL REGISTER

Chester J. Abend, Camillus, and Thomas E. Hanson and
Paul Dennis Younge, Syracuse, N.Y., assignors to SCM
Corporation, a corporation of New York

Filed Dec. 15, 1966, Ser. No. 5,061

Term of patent 14 years

(Cl. D52—4)

FIGURE 1 is a left front perspective view of the cash control register showing our new design;

FIGURE 2 is a front perspective view thereof;

FIGURE 3 is a left side elevational view thereof; and
FIGURE 4 is a rear elevational view thereof.

The undisclosed side is substantially the same in appearance as the side shown except for a knob adjacent the indicator portion.

We claim:

The ornamental design for a cash control register, substantially as shown and described.
